Primary Examiner — Derrick Holland*Assistant Examiner* — Jennifer O King(74) *Attorney, Agent, or Firm* — Seyfarth Shaw LLP; Brian Michaelis(57) **CLAIM**

The ornamental design for a casing for electrical devices, as shown and described.

DESCRIPTION

FIG. 1 shows a perspective view of a casing for electrical devices;

FIG. 2 shows a top plan view thereof;

FIG. 3 shows a bottom plan view thereof;

FIG. 4 shows a first side view thereof;

FIG. 5 shows a second side view thereof;

FIG. 6 shows a third side view thereof; and,

FIG. 7 shows a fourth side view thereof.

Opposite side views not shown are merely mirror images of the side view shown for each embodiment.
